MAHLON MATLACK, OF BRIDESBURG, (PHILADELPHIA,) PENNSYLVANIA.

Letters Patent No. 75,943, dated March 24, 1868.

IMPROVED APPARATUS FOR THE MANUFACTURE OF LAMP-BLACK.

The Schedule referred to in these Letters Patent and making part of the same:

TO ALL WHOM IT MAY CONCERN:

Be it known that I, MAHLON MATLACK, of Bridesburg, (Philadelphia,) in the county of Philadelphia, and State of Pennsylvania, have invented a new and improved Lamp-Black Apparatus; and I do hereby declare that the following is a full, clear, and exact description thereof, which will enable others skilled in the art to make and use the same, reference being had to the accompanying drawings, forming part of this specification, in which—

Figure 1 represents a longitudinal vertical section of my improved lamp-black apparatus.

Figure 2 is a vertical transverse section of the same, taken on the plane of the line xx , fig. 1.

Figure 3 is an under side view of the block in which the fire-pan is set.

Similar letters of reference indicate corresponding parts.

This invention relates to a new machine for producing lamp-black from suitable material, and consists in the construction and arrangement of the furnace and of the detaining-devices, by which the lamp-black is separated from the gases, and of the roof of the structure, all parts being so arranged that the operation of the apparatus will be complete, that no lamp-black will be allowed to escape with the gases, that no explosive gases can accumulate in any portion of the apparatus, and that the fire cannot reach any combustible portion of the apparatus.

A, in the drawing, represents the building or structure in which the gases containing the lamp-black are liberated. The roof of the building is made of slate or sheet-metal plates fastened to wooden beams. The slate or metal plates B B are fastened to the under side of the wooden beams C, as shown in figs. 1 and 2, for the purpose of preventing the flame in the building from reaching the wooden beams. The slates or plates B are either nailed to the beams by means of nails $a a$ clinched over the beams, as shown, or they are supported by metal bars $b b$, which are by means of staples or bolts cc suspended from the beams, as is also clearly shown in fig. 1, or otherwise. The flame in the building will thus strike against the incombustible lower face of the slates or metal plates, and in this manner a roof is obtained which is safe against danger from fire, and which is still light and cheaply made. D represents a partition arranged across the building A to form the dead-air chamber E for the ascent of the gas. F represents the furnace. The same is arranged opposite to the partition D, as shown, and has a bed or block, G, in which the pan H is set. The crown d above the pan is exceedingly low, as I have found that less of the lamp-black is burned if the crown is low, than when it is high above the pan. Some distance beyond the pan the crown may be gradually or suddenly raised, as indicated in figs. 1 and 2, in which a step, e, is shown for that purpose. In the bed G is arranged a channel, f, which carries heavy gases that may accumulate at the bottom of the building up to the fire again through crevices that are always formed around the pan. In this manner such dangerous gases will be burned, and they can therefore not explode under the furnace, which they do if confined in the ordinary manner. The pan is filled through an opening, g, in the furnace, and when its contents are lighted, the opening g is closed by a slide, h, as shown. The gases, liberated from the contents of the pan, enter the dead-air chamber through a hole, z, in the partition D, and strike against an inclined plate, j, arranged opposite that opening, as shown in fig. 1. They then will rise in the chamber E. In the chamber E is arranged a perforated damper, I, which has a plate, l, elevated somewhat above its hole, as shown. When the gas strikes against the plate l , it is suddenly deflected, and a large portion of the lamp-black contained in it is discharged upon the damper. The same effect is produced by the plate j . The damper can be turned whenever desired to discharge its load of black upon the floor of the chamber E. A series of such dampers, I, may be used, one above the other, if desired. From the upright chamber E, the gas enters a horizontal flue, J, in which the detaining-shelves $m m$ are arranged alternately on the top and bottom of the flue, as shown. By the same the last particles of the lamp-black are caused to leave the gas which then escapes through a pipe, n. Instead of the upper arrangement of the air-chamber E and its appendages, or in conjunction with the same, may be employed a fan, L. The same would serve to draw the gas down and to force it into a porous bag or vessel, M, through the walls of which the lamp-black cannot pass, while the gas can easily escape through the same. In this manner the lamp-black would at once be all thoroughly separated from the gas.

Having thus described my invention, what I claim as new, and desire to secure by Letters Patent, is—

1. Suspending the slates or sheets, which form the roof of a lamp-black apparatus, from the wooden beams C C of the same, substantially as and for the purpose herein shown and described.
2. Making the crown of the furnace low above the pan H, and gradually or suddenly raising it at some distance from the pan, as set forth.
3. Providing the bed G, which supports the pan H, with a gas-channel, f, substantially as and for the purpose herein shown and described.
4. The inclined plate j, arranged across the opening to the dead-air chamber E of a lamp-black apparatus, substantially as and for the purpose herein shown and described.
5. The perforated damper I, when provided with a plate, l, above the perforation, as specified.
6. The combination, with the dead-air chamber E having the damper I, of the horizontal flue J having the alternate up-and-down shelves m, as set forth.
7. The arrangement of the fan L, or its equivalent, by which the gas is forced into a porous vessel or bag in which the lamp-black is detained, as set forth.

MAHLON MATLACK.
